UNITED STATES PATENT OFFICE.

BENJAMIN J. NASIEF, OF BROOKLYN, NEW YORK, ASSIGNOR OF ONE-HALF TO ARTHUR H. HOTTE, OF MORRIS PARK, NEW YORK.

BLADE-SHARPENER.

1,217,981.

Specification of Letters Patent.

Patented Mar. 6, 1917.

Application filed February 28, 1916. Serial No. 80,949.

To all whom it may concern:

Be it known that I, BENJAMIN J. NASIEF, a subject of the Sultan of Turkey, residing at Room 502, Brooklyn Young Men's Christian Association, 55 Hanson Place, Brooklyn, in the county of Kings and State of New York, have invented certain new and useful Improvements in Blade-Sharpener, of which the following is a specification.

10 The present invention relates to blade sharpening apparatus and more particularly to the type in which the blade-holder and the sharpening element have a relative movement in an endless path, an object of this invention being to so arrange the blade-holder that it holds the blade at such an angle to the path of movement that all portions of the edge of the blade are wiped diagonally by the sharpening element thus insuring the best sharpening action. Another object of the invention is to provide in a blade sharpening apparatus of the type mentioned, means for automatically reversing the position of the blade holder so that 20 both edges of a blade in the holder may be presented to the sharpening surface. Another object of the invention is to provide a construction which is inexpensive to manufacture, simple in operation and not liable to 25 get out of order.

To these and other ends, the invention consists of certain parts and combinations of parts all of which will be hereinafter described, the novel features being pointed out in the appended claims.

In the drawings:—

Figure 1 is a plan view of a blade sharpening apparatus embodying the present improvement;

40 Fig. 2 is a view in side elevation of the same apparatus;

Fig. 3 is a transverse central sectional view;

45 Fig. 4 is a partial section on the line *a—a* of Fig. 3;

Fig. 5 is a section on the line *b—b* of Fig. 3;

Fig. 6 is a detail top plan of the blade holder support;

50 Fig. 7 is an end view of the same;

Fig. 8 is a top plan view of the blade-holder; and

Fig. 9 is an enlarged cross-section of the blade-holder on the line *c—c* of Fig. 8.

55 In the present embodiment of the inven-

tion the blade travels in an endless path over the sharpening element which is preferably in the form of a flat annular piece of leather 1 secured to a base 2 which has an upwardly-extending overhanging flange 3 at its periphery. A bail or handle 4 is pivoted in straps 5 struck up from the base 2, said handle serving to support the sharpening element on the hand of the user.

Mounted to move in an endless path over the sharpening surface 1 is a carrier 6 formed from a single piece of sheet material bent into inverted U-shape and having a horizontally presented portion 6^a at one end secured to the supporting-plate 2 by a pivot member 7. The other end of the carrier may be turned outwardly at 8 in order to guide the outer end of the carrier. A handle 9 may project upwardly from the carrier for effecting the movement of the latter relatively to the blade-sharpening surface.

In order to support the blade-holder, to be described, for movement toward and from the sharpening surface 1, a shaft 10 may 80 connect the arms of the U-shaped portion of the carrier so as to extend parallel with the sharpening surface. On this shaft is arranged an oscillatory member 12, the latter being preferably formed of a single 85 piece of material bent to provide, at opposite ends, two laterally-extending bearing portions 13 and 14 which surround the shaft 10. Also extending from the oscillatory member is a sleeve 15 in which the bearing 90 member 16 of the blade-holder 17 turns. The bearing member is provided with an annular groove 18 forming an annular shoulder 19 adapted to be engaged by spring 95 tongues 20 on the sleeve 15 for the purpose of holding the bearing 16 within the sleeve 15.

The blade-holder preferably embodies two plates 21 and 22 having parallel extending portions 24 for co-operating with opposite sides of a blade *x*, the portions of the plates in rear of the portion 24 being spaced apart to provide a pocket for receiving an enlargement on the rear edge of the razor blade. The plate 22 is provided with a rearwardly-extending flange 26 which is secured to the head 27 of the bearing 16. The flange 26 has recesses 25 at opposite sides for receiving lugs 29 on the plate 21 in order that the plate 21 may be moved relatively to the plate 110

22. U-shaped springs 23 are also received within the recesses 25 and engage both plates 21 and 22 to hold the latter toward each other for the purpose of clamping the portions 24 against opposite faces of the blade 26. A finger piece 28 may be extended from the plate 21 for the purpose of moving the latter away from the plate 22.

In order that the blade-holder may be rotated automatically about an axis extending transversely of the edge of the blade in the holder, there may be provided a roller or other device 30, preferably journaled at its ends in the arms of the carrier 6 and having a gear portion 31 thereon adapted to operate with the gear portion 32 on the arm 14 of the oscillatory member. By this arrangement when the carrier is moved in the direction of the arrow, Fig. 1, the roller 30 tends to throw the blade-holder downwardly to hold the edge of a blade against the sharpening surface, but when the carrier is moved in the opposite direction, the roller 30 by its frictional engagement with the sharpening surface is given a slight turn and transmits its movement to the oscillatory member thereby raising the blade-holder. On the upward movement of the blade-holder, one of the shoulders or projections 33 which are formed on opposite sides of the axis of the blade-holder is engaged by the device 34 in the form of a projection on the carrier 6. By this engagement, the blade-holder is turned on its bearings 16 so that when the carrier is again moved in the first direction, the blade-holder will be thrown downwardly to bring the opposite side of the blade edge into engagement with the sharpening surface.

40. From the foregoing, it will be seen that there has been provided a construction in which a relative movement takes place between a blade-holder and a sharpening element in an endless path, the blade-holder being arranged at such an angle to the path of movement that all portions of the blade-edge are wiped diagonally by the sharpening surface. This is due in the present embodiment to the fact that the blade travels about 45 an axis normal to the plane of the sharpening surface and has all portions of its edge lying at an angle to the tangent of any circle concentric with the turning axis and intersecting the blade-edge, said tangent being drawn from the point of intersection. In this instance also the turning axis of the blade which lies transversely of the blade-edge, is at an angle other than a right angle to the turning axis of the oscillatory member.

45. The apparatus also provides for turning the blade-holder about an axis extending transversely of the cutting edge of a blade in the holder, so that a relative movement between the blade-holder and the sharpen-

ing element can take place in an endless path.

There has also been provided an inexpensive structure which has simple operations for producing the above result.

What I claim as my invention and desire to secure by Letters Patent is:

1. A blade sharpening apparatus comprising a sharpening element, a blade holder, one of said elements being movable in an endless path, and mechanism interposed between the sharpening element and the blade-holder normally tending to move one toward the other, said mechanism operating on the reversal of the normal movement to separate the blade-holder and the sharpening element and to rotate the blade-holder about an axis transverse to the edge of a blade held in said blade-holder.

2. A blade sharpening apparatus, comprising a blade sharpening element, a blade-holder, one of said elements being movable in an endless path, an oscillatory member on which the blade-holder is mounted to rotate, and mechanism operating between said oscillatory member and the blade sharpening element whereby the oscillatory member is moved to carry the blade away from the sharpening element when the direction of movement between the latter and the blade-holder is reversed.

3. A blade sharpening apparatus, comprising a blade sharpening element, a blade-holder, one of said elements being movable in an endless path, an oscillatory member on which the blade-holder is mounted to rotate, a member frictionally bearing against the blade sharpening element and operating upon the oscillatory member to cause the latter to carry the blade-holder away from the sharpening element when the direction of movement between the sharpening element and the blade-holder is reversed.

4. A blade sharpening apparatus comprising a blade sharpening element, a blade-holder, one of said elements being movable in an endless path, an oscillatory member on which the blade-holder is mounted to rotate, mechanism operating between said oscillatory member and the blade sharpening element whereby the blade-holder is caused to move away from the blade sharpening element when the direction of movement between the sharpening element and the blade-holder is reversed, and a device arranged to rotate the blade-holder on the oscillatory member when the blade-holder moves away from the sharpening element.

5. A blade sharpening apparatus, comprising a blade sharpening element, a blade-holder, one of said elements being movable in an endless path, an oscillatory member on which the blade-holder is mounted to rotate, a roller bearing against the blade sharpening element and connected to the oscillatory

member to move the blade-holder away from the sharpening element when the direction of movement between the blade-holder and the sharpening element is reversed, and a device arranged to rotate the blade-holder on the oscillatory member when the blade-holder is moved away from the sharpening element.

6. A blade sharpening apparatus, comprising a flat blade sharpening element, a carrier rotatable on said element about an axis normal to the plane of the sharpening element, an oscillatory member mounted to swing on said carrier about an axis parallel to the

plane of the blade sharpening element, a roller engaging the blade sharpening element and connected to the oscillatory member to swing the same in opposite directions upon the movement of the carrier in opposite directions, a blade-holder mounted to turn on said oscillatory member about an axis transverse to the edge of a blade in said holder, and a device arranged on the carrier for engaging the blade-holder on opposite sides of its turning axis to cause it to turn when it is carried away from the sharpening element.

BENJAMIN J. NASIEF.
